UNITED STATES PATENT OFFICE.

THOMAS C. LAZIER, OF BELLEVILLE, CANADA, ASSIGNOR, BY MESNE ASSIGNMENTS,
TO NATURAL AIR DRYERS, INC., A CORPORATION OF DELAWARE.

DRYING APPARATUS.

Application filed September 27, 1919, Serial No. 326,800. Renewed January 13, 1923.

To all whom it may concern:

Be it known that I, THOMAS C. LAZIER, a citizen of the Dominion of Canada, residing in the city of Belleville, Canada, have invented a certain Improvement in Drying Apparatus, of which the following is a specification.

In certain United States patents to Seymour W. Bonsall, and notably in his Patent Number 1,047,734, dated December 17th, 1912, there are described and claimed certain forms of rotary driers depending for operation upon the principle of subjecting the materials to be dried to the action of a current of air which is compressed by being forced through narrow passages between the surfaces of the articles to be dried.

My present invention relates to a novel and improved form of drying apparatus for applying the same general principle of operation as is utilized in the Bonsall patent aforesaid to the drying of various materials and more especially to drying shingles. The invention in its narrower aspects relates to an improved package of shingles particularly adapted to be inserted within my improved drier, as well as to the special supports for such package which forms a detachable element in my apparatus.

The invention is illustrated in a preferred form in the accompanying drawings, wherein Figure 1 is a plan view of my preferred drier, showing a portion broken away to reveal the interior, Figure 2 is a front elevation of the drier, Figure 3 is a side elevation of the containing frame showing the same partly filled, Figure 4 is a perspective view of one supporting track, Figure 5 is a plan view of a shingle-supporting unit, Figure 6 is a side elevation of the same showing a portion of a side bar removed, and Figure 7 is an end view of one side of the same.

My improved drier is composed of a plurality of elements each comprising a scoop-shaped intake passage or flue and a drying passage or flue forming a continuation of the intake flue and directed away therefrom. Two or more elements of this kind are mounted so as to balance each other upon

a revoluble mounting which, in the form 50 shown, is set up vertically. In the present instance I have shown the apparatus as preferably equipped for drying shingles, but the invention in its broadest aspect is not limited to this modification. 55

In the preferred form shown my drier is composed of two air boxes, 10 and 11, mounted symmetrically upon the shaft 12, which may be revolved by any suitable means, as for instance, the gears 13 and 14. 60 Each box terminates on one side of the shaft 12 in a scoop-shaped intake, 15, 16, and this leads through a sharply curved air collecting flue having its continuation in the drying flue whose top is shown broken away in 65 the lower part of Figure 1. In the preferred form shown, the outer side of the drying flue is made in the form of a door 17, hinged at 18, so that, when this door is swung open, the material to be dried may be 70 loaded through this doorway from the platform 19. When closed, this door may be confined by any appropriate means, as for instance, the locks 20 and 21, on the upper and lower outer corners of the door, engaging 75 the roof and floor of the drier, respectively.

In order to carry out the purpose of the invention in accordance with the principles of operation set forth in the Bonsall patent 80 aforesaid, it is necessary to so dispose the shingles or other material treated that narrow passages are formed through which the large volume of air collected is forced to travel in a compressed condition. For practical purposes it is also important that means be provided whereby the material and its supporting medium shall be easily balanced in opposing members or elements. 85 For these purposes, and to save time and labor in preparing and loading, I have devised the removable container shown in my drawings. 90

This container comprises a number of independently separable supporting units, 95 carried symmetrically upon a movable frame. The preferred supporting unit is shown in Figures 5, 6 and 7.

This unit comprises parallel flat vertically set side plates 22, 23, mounted upon wheels 24, which are preferably flanged, as shown. The ends of the side plates are joined by 5 parallel, horizontally set, flat end plates 25, 26, thus completing a rectangular frame, the component plates in which are all set edge-wise with relation to any air current which may approach it in a longitudinal direction 10 (parallel to the side plates).

Placed parallel with the side plates there are provided holding rods 27 whose ends are supported by and secured to the end plates 25 and 26. For this purpose the ends of the 15 rods are preferably passed through holes in the end plates, being bent back into horizontal position at their extremities as shown best at 28 in Figures 6 and 7.

The holding rods 27 are placed at such 20 a distance apart as to make contact with opposite faces of the tapering shingles 30 near the butts thereof, when these shingles are dropped sharp edge downward between said rods. It will thus be seen that the loading 25 of the shingles involves the minimum of time and labor, since it is only necessary to place each supporting unit in turn in front of the chute delivering the shingles, sharp edge down, through the spaces between the holding rods. The side edges of 30 contiguous shingles should touch, and there will thus be formed a number of vertical passages, very narrow in cross section, separated by walls constituted by the shingles 35 themselves. These passages extend from end to end of the supporting units.

The units thus loaded are next united in 40 a container frame in such a manner as to bring the narrow air passages in one unit into line with those in the units above and below the same; thereby constructing a series of flat narrow air passages side by side from top to bottom of the container, and consequently from top to bottom of the drying 45 flue in the box 10 or 11, into which containers of this kind are fitted. (See Figures 1 and 2.)

The preferred container frame comprises 50 a base 31 on wheels 32, carrying four corner posts 33, side posts 34, and top bars 35 and 36. Carried by the posts 33 and 34 respectively, are transverse tracks 37, parallel to the axes of the wheels 32.

The supporting units, having been loaded 55 as described are placed in the container by setting their wheels 24 upon the tracks 37, and pushing them in until their frames come against the stops 38. When all the tracks are thus occupied the entire container 60 will be divided by narrow flat vertical passages running transversely with relation to the direction in which the wheels 32 of the container are set.

It will thus be seen that, when the door 65 17, of the drying flue on one side of the

drier is opened, and a container thus loaded is rolled from the platform 19 into the flue, filling it both horizontally and vertically, the result will be the formation of a composite drying flue whose elementary 70 passages are of the desired narrow character, set edgewise to the direction of the air current in the flue, and whose walls are constituted by the shingles to be dried. As already remarked, the structure of the container is such that all the structural material takes the form of thin rods or plates set lengthwise and edgewise to the current. The round holding rods, moreover, present a mere line of contact with the shingles, and 80 there is practically no part of the shingle surfaces shielded from the air.

When both sides of the drier are thus loaded, the doors 17 are closed and secured, and the entire drier is then caused to revolve in the direction of the arrow in Figure 1. This revolution will cause the air collected by the two scoops to be forced in a compressed state at a high rate of speed 85 through the narrow passages above described. As described in the patent to Bon-sall above specified, this will cause the shingles to be subjected, not only to surface evaporation, but to an exhausting effect exerted at the eternal orifices of the moisture 90 containing capillaries or pores of a nature familiar in machines for exhausting electric lamp bulbs and in other connections.

Various changes may be made in my apparatus without departing from the scope of 100 my invention, and I do not limit myself to the details herein shown and described.

What I claim is:—

1. Drying apparatus comprising a plurality of revolvably mounted elements balanced around their center of revolution, 105 each element comprising an intake scoop and flue and a drying flue forming a continuation of the same and directed away from the intake opening.

2. Apparatus of the character set forth in claim 1 hereof wherein the elements are mounted upon a vertical shaft provided with means for driving the same.

3. Apparatus of the character set forth 115 in claim 1 hereof, wherein the outer wall of the drying flue is provided with a door adapted to permit loading of the material therethrough.

4. In combination with the other features 120 of a revolvable drier, a separable container comprising a wheeled frame and independent supporting units adapted to be inserted in said frame, wherein the container is supplied with pairs of tracks, and wherein the 125 supporting units are provided with wheels fitting upon said tracks.

5. Apparatus of the character set forth in claim 4 hereof, wherein the independent supporting units are constructed of plates 130

set edgewise to the expected direction of air currents, and holding means on said plates.

6. A supporting unit for carrying shingles, comprising parallel holding rods set at such distance apart as to touch the two faces of a shingle inserted sharp edge downward between them, and means for supporting said rods wherein round rods are used which 10 are supported by a frame made of plates set edgewise with respect to the direction of the rods.

7. In drying apparatus of the general character described, a composite drying flue comprising a group of narrow elementary 15 drying flues separated by walls composed of superposed rows of parallel shingles all set edgewise to the expecting direction of the air current.

In testimony whereof I have hereto set 20 my hand on this 23rd day of September, 1919.

THOMAS C. LAZIER.
